US00D947141S

(12) **United States Design Patent** (10) **Patent No.:** **US D947,141 S**
Deng (45) **Date of Patent:** **** Mar. 29, 2022**

(54) **REMOTE CONTROL**

(71) Applicant: **Shenzhen FurryKid Technology co., Ltd**, Shenzhen (CN)

(72) Inventor: **Hao Deng**, Shenzhen (CN)

(**) Term: **15 Years**

(21) Appl. No.: **29/748,544**

(22) Filed: **Aug. 31, 2020**

(51) LOC (13) Cl. **14-03**

(52) U.S. Cl.

USPC **D13/168; D30/199**

(58) **Field of Classification Search**

(57) **CLAIM**

The ornamental design for a remote control, as shown and described.

DESCRIPTION

FIG. 1 is a first perspective view of a remote control showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the remote control in which the design is embodied that form no part of the claimed design.

1 Claim, 8 Drawing Sheets
